(57) **CLAIM**

The ornamental design for a saddlebag lid, as shown and described.

DESCRIPTION

FIG. 1 is a rear perspective view of the saddlebag lid; FIG. 2 is a front perspective view of the saddlebag lid; FIG. 3 is a right side elevation view of the saddlebag lid; FIG. 4 is a left side elevation view of the saddlebag lid; FIG. 5 is a bottom plan view of the saddlebag lid; FIG. 6 is a top plan view of the saddlebag lid; FIG. 7 is a rear elevation view of the saddlebag lid; and, FIG. 8 is a front elevation view of the saddlebag lid.

The drawings show the design of a saddlebag lid suitable for positioning on the left side of a vehicle. The ornamental design also includes the mirror images of the drawings, i.e., the design of a saddlebag lid suitable for positioning on the right side of the vehicle.
